UNITED STATES PATENT OFFICE.

ALBERT N. KLYVER, OF SYRACUSE, NEW YORK, ASSIGNOR TO THE LAMSON COMPANY,
OF SYRACUSE, NEW YORK, A CORPORATION OF MASSACHUSETTS.

CONVEYER SYSTEM.

Application filed March 29, 1927. Serial No. 179,206.

This invention relates to certain new and useful improvements in conveyer systems.

The invention pertains more specifically to an automatic means for selectively diverting carriers from one track into any one of a number of other tracks, and the main object of the invention is to provide for a substantial increase in the number of selector devices whereby a corresponding increase in the number of main tracks and branch tracks leading therefrom may be effected.

Heretofore structures have been used in which a tab or feeler finger is mounted in some manner to lie in the path of movement of selecting pins which extend upwardly from the carrier or box moving along the conveyer, and the tabs have been disposed at various positions transversely of the conveyer for actuation by different pins arranged in a row transversely of the carrier, but in all such structures the number of selecting pins has been limited to the number that can be arranged in a single row transversely of the carrier whereby the number of different main tracks and branch tracks into which carriers are automatically deflected by a pre-determined arrangement of selector pins has been correspondingly limited, and this invention provides a structure in which the number of available positions for selector pins or devices may be increased to any desired extent by the use of pins terminating at different elevations above the carriers in combination with special operating tabs, resulting in marked advantages in a conveyer system.

A further object resides in the particular construction of the tab mechanism separately and in combination with a number of transverse rows of sockets for selector pins or devices terminating at different heights above the carrier and in which a pin of a particular height only in line with a particular tab actuates that tab to operate a switch or deflecting bar, whereby carriers moving along the conveyers are deflected on to another or branch track and any pin or pins which project a greater distance above the carrier are adapted to move the tab to permit the passage of these higher pins, if any, independently of and without effecting a movement of the switch, or deflecting bar so that the carrier may pass freely along without deflection and any pin or pins of lesser elevation pass freely under the tab without moving the tab.

Other objects and advantages relate to the detail of the structure and the form and relation of the parts thereof, all as will more fully appear from the following description taken in connection with the accompanying drawings, in which:—

Figure 1 is a fragmentary plan view of a conveyer system embodying this invention.

Figure 2 is a fragmentary elevation of a portion of the conveyer system shown in Figure 1.

Figure 3 is a vertical section through the tab mechanism of this invention, and through a fragmentary portion of a carrier illustrating three selecting pins of varying heights arranged in line, one behind the other.

Figure 4 is an elevation of the tab mechanism of this invention.

Figure 5 is a vertical section through the tab mechanism.

Figure 6 is a view partially in section of a tab adapted to be used for actuation by the highest pin, the other pins in line passing beneath the tab.

Figure 7 is an elevation of the latch and its releasing mechanism.

The apparatus here illustrated as an embodiment of the invention comprises a main track having side rails —1— and —2—, such rails being provided with series of journals —3— for the reception of the axles of rollers —4—. Resting upon the several rollers is the upper run of an endless belt —5—, the lower run of which is not illustrated. Such belt may be driven from any suitable source of power and in any suitable and well known manner.

Diverging from the main track is a second track comprising the side rails —6— and —7— having journal openings for the axles —8— of a series of rollers —9—. This second or branch track may or may not be provided with an endless belt, as desired, and is here illustrated as not provided with power-driven impelling means and represents, for instance, the upper end of a downwardly inclined gravity conveyer track. However, it will be understood that this disclosure is merely illustrative of a fragmentary embodiment of the invention, and is in nowise limited thereby.

A guide rail —10— is provided extending from the main track some distance along the side of the branch track to prevent carriers moving along the track from being thrust

sidewise off the conveyer tracks when deflected by the action of the switch bar —11—.

At a point adjacent the juncture of the branch track with the main track there is provided a pair of upright posts —12— positioned upon opposite sides of the main track and secured respectively to the side rails —1— and —2—.

These posts extend some distance above the main track and are provided with brackets —13— in which the transversely extending rock shaft —14— is journaled. The rock shaft —14— is positioned some distance above the main track so as to be out of the path of movement of the carriers moving along the track and the rocking movement of the shaft —14— is designed to actuate the switch or deflecting bar —11—. This deflecting bar —11— is shown in its normal position in full lines (Fig. 1) and is out of the path of movement of carriers passing along the main track, and for the purpose of shifting the switch bar to a position diagonally across the main track, the shaft —14— is provided with a crank-arm —15— connected by link —16— to another crank-arm —17— secured to shaft —18— journaled in bearings upon the post —12— below the side rails —1— and —2— of the main track.

The shaft —18— extends transversely of the main track and at a point adjacent the side rail —1— it is provided with a crank-arm —18— connected by a link —19— to a crank-arm —20— secured to a vertical shaft —21— journaled in bearings —22— secured to the side rail —1— and the longitudinal frame bar —23—.

The switch or deflecting bar —11— is secured to the rock shaft —21— in any suitable manner, and at a point preferably slightly above the upper run of belt —5—. A brace bar —24— is secured to the upper end of shaft —21— and has its other end connected to the deflecting bar —11— near the outer end of the latter.

Spring means is preferably provided for maintaining the deflecting bar in the position shown in Figure 1 with its end portion in contact with the stop —25— and for the purpose of illustration, there is here shown spring —26— connected to a bracket on the side rail —1— and to the end of the rock-arm —20—.

Suitable mechanism is provided for rocking the shaft —14— to shift the switch or deflecting bar —11— to the position shown in dotted lines (Figure 1) diagonally of and across the main track, and the deflecting bar may be temporarily held in this position by a latch mechanism —27— of any suitable and well known construction, and released in any suitable and well known manner, as for instance by the passage of a carrier over an actuating lever —28— disposed in the

path of movement of a carrier moving along the branch track. This actuating lever —28— is mounted on a rock shaft —80— journaled in the side rails —6— and —7— and whenever a carrier rests on the lever —28— the shaft is rocked, in turn rocking arm —81— connected by link —82— to a rock arm —83— on shaft —84— which in turn rocks arm —85— on shaft —84— to draw the latch —27— downwardly 75 against the action of spring —87—, thereby releasing deflecting bar —11— which returns to normal position and deflecting bar will not be again latched in its carrier deflecting position until the carrier moves from contact with the lever —28— so that when branch track is full no further carriers will be directed into it.

As stated, when the deflecting bar —11— is released by the latch mechanism —27—, 85 it is returned to the normal position shown in full lines (Figure 1) by spring —26— to permit the free passage of carriers along the main track.

The tab mechanism of this invention comprises a main lever —30— preferably consisting of an elongated strip of metal having its end formed with a bearing for the reception of the shaft —14—. The main lever —30— is free to rotate or rock about the shaft —14— without effecting the movement of the shaft. In addition, the shaft —14— adjacent the lever —30— is provided with a rock-arm —31— pinned or otherwise secured to the shaft for simultaneous rocking movement and the rock arm —31— is provided with a pin or stud —32— in front of the lever —30—.

At an intermediate point along the length of the lever —30— there is provided a U-shaped bracket —33— having its base secured to the lever —30— and its two sides projecting rearwardly therefrom and spaced apart and provided with openings in which the shaft —34— is journaled for rotary movement. A second lever —35— is mounted upon the shaft —34— and this lever may be in the form of a strip of metal having one end bent around the shaft —34— and pinned or otherwise secured thereto for simultaneous rotary movement.

In addition, outside the U-shaped bracket —33— a latch member —36— is mounted upon the shaft —34— and pinned or otherwise secured thereto for simultaneous rotary movement, and the hook end —37— of the latch is adapted to normally engage or lie slightly forwardly of the rock-arm —31—.

In order to normally maintain the latch mechanism and the lever —35— in the position shown in Figure 3, a spring —38— is provided positioned between the head —39— of a bolt —40— which extends through an opening in the lever —35— and is secured to the lever —30— in any suitable manner, as 130

by nut 41 , the opening in the lever 35 being somewhat larger than the bolt.

In addition, at the lower end of the lever 35 there is provided a stud 42 secured to the lever 35 and extending through an opening in the lever 30 and projecting some distance forwardly of the lever 30 in normal position of the tab mechanism, and provided at its end with a contact plate or disk 44 with which certain of the selecting pins are adapted to contact.

The opening in the lever 30 through which stud 42 extends is somewhat larger than the cross-sectional area of the stud to permit free movement of the stud through the lever 30 .

The forward portion of a carrier A is illustrated in Fig. 3 and at the front end 20 of the carrier there are provided in this embodiment three transverse rows of sockets 45 , 46 and 47 of different depth and in which transverse rows of pins 48 are adapted to be inserted. A pin 48 in socket 45 projects above the upper surface of the carrier a distance somewhat greater than a pin 48 in socket 46 and in a similar manner a pin 48 in a socket 46 projects above the upper surface 25 of the carrier a distance somewhat greater than a pin 48 in a socket 47 .

In the structure shown in Figure 4, the pin 48 as for instance in a socket 46 is designed for actuating the tab mechanism 35 there shown to move the switch or deflecting arm 11 to a position diagonally of the main track whereby the carrier A will be deflected on to the branch track, and this is effected by the pin 48 striking the lower end of the lever 30 and moving the same forwardly.

Such movement of lever 30 carrying the latch 36 into contact with the rock-arm 31 to thereby rock shaft 14 and actuate the deflecting arm 11 through medium of the crank arms and link arms described.

The movement of the tab by the pin 48 is of sufficient extent to move the deflecting arm to the position shown in dotted lines (Figure 1).

As a general rule, each carrier will be provided with a single pin adapted to move a particular tab mechanism to actuate a pre-determined switch or deflecting bar. However, in some cases a plurality of pins may be utilized. Preferably all pins are formed of the same length and are utilized in connection with sockets of different depth, as illustrated, but it is possible to accomplish the objects of this invention by utilizing sockets of the same or substantially the same depth in connection with pins of different lengths.

In Figure 3 there is illustrated a pin in

one of the sockets 45 and this pin is adapted to terminate at a higher elevation than pins in the sockets 46 and 47 aligned with the socket 45 but at the rear thereof. As shown, the pin 48 in the socket 45 of Figure 3 is not intended to operate the deflecting bar which is actuated by the particular tab mechanism shown, but is designed for actuating some other switch operated by another tab mechanism such as that shown in Fig. 6, and for that reason it must pass by the tab mechanism shown in Figure 3 without rocking the shaft 14 , and this is effected by reason of the fact that the pin projects sufficiently above the carrier and a sufficient distance upwardly along the tab mechanism so as to come in contact with the disk 44 thereby rocking the lever 35 and the latch 36 to release the engagement of the latter with the rock shaft 31 to permit free rocking of the tab mechanism without rocking shaft 14 and therefore, without actuating the deflecting bar adapted to be operated by this particular tab.

The pin 48 in socket 46 shown in dotted lines (Figure 3) will in the same manner strike contact disk 44 and release the tab from engagement with the rock shaft 14 and the carrier will move freely along the track without deflection. A pin inserted in the socket 47 in line with the tab mechanism of Figure 3 will strike the lower end of lever 30 without releasing the latch 36 and in its movement will therefore rock shaft 14 to operate the switch or deflecting bar connected to the shaft and the carrier will be deflected into the pre-determined track. As shown in Figure 4, if the pin illustrated in full lines and adapted to rock shaft 14 is a pin 48 in one of the sockets 46 , a pin 48 in a socket 47 will pass underneath the lever 30 and will not actuate the deflecting bar.

In view of the fact that only the pins that extend to the highest elevation above the carrier will strike the tab 60 , all other pins passing underneath it, it is not necessary that the tab 60 should be provided with any means for releasing it from the shaft 14 , and for that reason it may be rigidly secured to the shaft, as illustrated.

From the above description, it will be apparent that a desired number of transverse rows of sockets may be formed in a single carrier for use in connection with pins adapted to terminate at different elevations above the carrier, and that the deflecting mechanism will be actuated only by a pin of a proper height to strike the lower end of the lever 30 without contact with disk 44 , and that the deflecting mechanism will not be actuated by pins of a

height to strike the disk —44—, nor by pins of a height to pass underneath the lever —30—, and by reason of this construction and arrangement of parts which permits the use of a plurality of rows of sockets for receiving selecting pins a greatly increased capacity of apparatus may be produced in which independent selective means is provided for determining the particular track 10 onto which a carrier is deflected.

In the drawings I have illustrated a single main track and one branch leading therefrom, and a single switch and switch-operating mechanism. However, it will be understood that any number of main tracks may be utilized, and that any number of branch tracks may lead from each main track within the capacity of the sockets provided for the reception of selecting pins, and that at 20 each branch track a tab mechanism similar to that shown in Figure 3 is provided which depends above the track the proper distance to be actuated either with or without actuating the deflecting bar in accordance with the 25 height of the particular pin which contacts with the tab mechanism, except that the tab mechanism shown in Figure 6 may be utilized in connection with deflecting or switch mechanism to be actuated by pins which 30 terminate at the highest elevation above the carrier. For that reason, my invention broadly contemplates a plurality of tab mechanisms terminating at different elevations above the track combined with a plurality of selecting devices also terminating at different elevations above the track to 35 correspond with the points of termination of the respective tabs so that certain pins of certain heights will pass underneath the tab, 40 certain pins of a different height will actuate the tab to operate the switch mechanism, and certain pins of a still different height will actuate the tab without operating the switch mechanism.

45 And altho I have shown and described a specific construction of apparatus and particular details of form and arrangement of the parts thereof as constituting an embodiment of the invention, I do not desire to 50 restrict myself to the same as various changes and modifications may be made within the scope of the appended claims.

I claim:

55 1. In a device of the class described, in combination, a deflecting mechanism, actuating members of varying heights disposed to engage such mechanism, means whereby an actuating member of a given height upon engagement will operate said mechanism, 60 and means whereby actuating members of different heights will engage said mechanism without making it operative.

65 2. In a device of the class described, in combination, a deflecting mechanism, an intermediate member releasably engaged with

such mechanism, actuating members of varying heights disposed to engage said intermediate member successively, and means whereby such actuating members except one of a predetermined height engaging said 70 intermediate member will release the same from engagement with said mechanism.

3. In a conveyer system a conveying means, cars carrying selecting pins of varying heights, a deflecting mechanism, means 75 whereby such mechanism will be made operative when engaged by pins of a given height, and means whereby pins of other heights may engage said mechanism without causing it to become operative. 80

4. In a conveyer system, a conveying means, cars carrying pins of varying heights, a deflecting mechanism, an intermediate member of said mechanism disposed in the path of said pins, means whereby all pins 85 of a given height engaging said intermediate member will make operative said deflecting mechanism, and means whereby pins of different heights engaging said intermediate member will release the same from 90 the deflecting mechanism.

5. A conveyer system comprising a carrier having a plurality of transverse rows of selecting pin sockets for supporting pins terminating at different heights above the 95 carrier, a switch, tab mechanism moved by a pin of one height to actuate the switch and moved by a pin of a different height without actuating the switch.

6. A conveyer system comprising a carrier having a plurality of transverse rows of selecting pin sockets adapted for supporting pins terminating at different heights above the carrier, a switch and a tab mechanism moved by a pin of one height to actuate the 100 switch and moved by a pin of a different height independently of the switch. 105

7. A conveyer system comprising a carrier, a switch, sockets for receiving selecting devices arranged one behind the other 110 upon the carrier lengthwise of the conveyer and adapted for supporting pins terminating at different heights above the carrier, a rock shaft, a tab mechanism mounted on the shaft to rock the shaft but releasable 115 therefrom for free rocking movement when actuated by a pin of pre-determined height.

8. In a device of the class described, a deflecting mechanism, a plurality of actuating members successively engaging said mechanism, and means whereby certain actuating members may engage said mechanism without actuating the deflecting member of said mechanism. 120

9. In a conveyer system a deflecting mechanism, a plurality of actuating members adapted to engage with a portion of said mechanism, and means whereby said mechanism is not operated when engaged by certain of said actuating members. 125 130

10. A conveyer system comprising a main track and a branch track, a deflecting bar, a rock shaft for actuating the deflecting bar, a tab rotatably carried by the rock shaft, a carrier including a plurality of sockets arranged one behind the other for receiving pins of different heights, means for rocking said shaft in accordance with the movement of the tab mechanism when a pin of pre-determined height contacts with said mechanism and for releasing said tab mechanism from the rock shaft and permitting it to freely rotate thereon when a pin of a different height contacts with said mechanism.
15. 11. In a conveyer system a deflecting bar, a rock shaft for actuating the deflecting bar, a lever rotatably mounted on the rock shaft, a second lever rotatably mounted on the first named lever, and means supported by the first named lever and adapted for actuation by the second named lever for securing the first-named lever to the rock shaft whereby rocking movement of the first-named lever rocks the shaft.
20. 12. In a conveyer system a deflecting bar, a rock shaft for actuating the deflecting bar, a tab for actuating the rock shaft including a lever rotatably mounted on the shaft, a second lever rotatably carried by the first lever, a latch rocked by movement of the second named lever and a rock arm rigidly secured to the rock shaft and adapted to engage the latch.
25. 13. In a conveyer system a deflecting bar, a rock shaft for actuating the deflecting bar, a tab for actuating the rock shaft including a lever rotatably mounted on the shaft, a second lever rotatably carried by the first lever, a latch rocked by movement of the second named lever, a rock arm rigidly secured to the rock shaft and adapted to engage the latch, and spring means normally holding the second named lever in a position where the rock arm and latch are engaged.
30. 14. In a conveyer system, a deflecting bar, a rock shaft for actuating the deflecting bar, a tab for actuating the rock shaft including a lever rotatably mounted on the shaft, a second lever rotatably carried by the first lever, a latch rocked by movement of the second named lever, a rock arm rigidly secured to the rock shaft and adapted to engage the latch, a rock arm rigidly secured to the rock shaft and adapted to engage the latch, and spring means normally holding the second named lever in a position where the rock arm and latch are engaged.
35. 15. In a conveyer system a lever rotatably mounted on the shaft, a second lever rotatably carried by the first lever, a latch rocked by movement of the second named lever, a rock arm rigidly secured to the rock shaft and adapted to engage the latch, spring means normally holding the second named lever in a position where the rock arm and latch are engaged, and a contact member carried by the second named lever and adapted to be engaged by a portion of a carrier moving along the conveyer system to rock the second-named lever and release the rock arm from its engagement with the latch.
40. 16. In a device of the class described, in combination, a deflecting mechanism, an intermediate member releasably engaged with said mechanism, actuating members of varying heights disposed to engage said intermediate member in rotation, means whereby all actuating members of a predetermined height engaging said intermediate member will release said intermediate member from engagement with said mechanism.
45. 17. In a conveyer system including a track, a switch mechanism, a plurality of tabs depending above the track and terminating at different elevations above the track, carriers having selecting members terminating at different elevations above the track for actuating different tab mechanisms to operate respective switches and for rendering other tab mechanisms inoperative to actuate their respective switches.
50. 18. In a conveyer system, a track, cars movable along the track, actuating members extending different distances from the car or cars, a deflecting mechanism, and means whereby an actuating member extending one distance from a car upon engagement will operate said mechanism, and means whereby an actuating member extending a different distance from the car will engage said mechanism without making it operative.
55. 19. In witness whereof I have hereunto set my hand this 25th day of March 1927.

ALBERT N. KLYVER.
